UNITED STATES PATENT OFFICE.

CHARLES F. HANSELMANN, OF BROOKLYN, NEW YORK.

CHART FOR TUNING RADIO SETS.

Application filed September 26, 1923. Serial No. 685,031.

To all whom it may concern:

Be it known that I, CHARLES F. HANSELMANN, a citizen of Germany, and a resident of the city of New York, borough of Brooklyn, in the county of Kings and State of New York, have invented a new and Improved Chart for Tuning Radio Sets, of which the following is a full, clear, and exact description.

10 This invention relates to improvements in recording devices, and has particular reference to a chart for tuning radio sets.

An object of the invention is to facilitate the repeated tuning of the various instruments of a radio set for any particular station by providing a chart in which a plurality of indicating devices, each corresponding to a different tuning instrument of said set, are operated to record the positions of 20 the dials or switches associated with said instruments when the latter are tuned to a definite wave length individual to said station.

The above and other objects will appear 25 more clearly from the following detail description when taken in connection with the accompanying drawing, which illustrates preferred embodiments of the inventive idea.

80 In the drawing.

Figure 1 is a fragmentary plan view of the chart constructed in accordance with the invention;

Figure 2 is a longitudinal section therethrough;

Figure 3 is a fragmentary plan view of a slightly different form of the invention; and

Figure 4 is a fragmentary plan view of still another form of the invention.

Referring particularly to Figures 1 and 2, the chart is shown as comprising a base or body portion 4, which may be made of any suitable material and the face of which is provided with a plurality of horizontal lines 5 arranged in parallel relation to divide the chart into a plurality of rows. Other vertical lines 6 intersecting the lines 5 divide the chart into vertical columns and combine with the lines 5 to divide the chart into a plurality of rectangular spaces for purposes which will presently appear. In the space 7 at the top of the column shown at the extreme left end of the chart, the word "Stations" or any other desirable designation is inserted and in the remaining spaces in said column the station letters individual

to various broadcasting stations are inserted, each of the latter spaces and the station letters therein being individual to the row in which said space is located. The spaces at 80 the top of the other columns contain indicia designating the various tuning instruments forming a part of the radio set, such as primary and secondary coils, condenser, vario-coupler and other instruments. For each of the instruments of the set there is provided in each row a dial 8 having graduations thereon similar to the graduations on the dial associated with the corresponding instrument of the set. Each dial is 70 formed of any suitable material and is rotatably mounted on a rivet 9 or other similar device, which is extended through the dial and the base 4, as clearly shown in Figure 2. Associated with each dial and marked 75 in the spaces in which said dial is located is an indicator 10 arranged adjacent the periphery of the dial.

After the operator of the radio set has initially tuned the instruments of a set to the proper wave length or frequency for any particular broadcasting station, the various dials of the chart individual to said station may be rotated and set in accordance with the settings of the corresponding dials of the 85 radio set, thereby establishing a permanent record, which will enable the operator to quickly adjust the instruments of the set when it is subsequently desired to tune in on 90 any particular station.

In the form of the invention shown in Figure 3, the base 4 is again divided into columns and rows with the spaces in the left-hand column having the usual station designations. Instead of the dials 8, however, the spaces of the remaining columns contain representations 11 of what is generally known as tap switches used in conjunction with certain instruments of a radio set. Associated with each of the representations 100 11 is a rotatably mounted pointer or indicator 12, which may be adjusted to a position similar to the rotatable contact member of a tap switch for a purpose which will now be apparent.

In the form of the invention shown in Figure 4 each of the spaces of the chart may have printed or otherwise indicated thereon a representation of a dial 13, similar to the dials 8, which dials 13 may be marked with 110 a pencil or an ink line 14 by the user of the chart as a permanent record for indicating

the position to which the corresponding dial of the radio set must be adjusted for any particular station.

What is claimed is:

- 5 1. As a new article of manufacture, a chart for tuning radio sets, including a base having on one surface thereof a plurality of intersecting lines dividing said surface into spaces forming a plurality of columns and 10 rows, the spaces in one of said columns containing station designations, and a recording device corresponding to one tuning instrument of the radio set in each of the spaces in the row opposite each of the station 15 designations and capable of being adjusted to provide a permanent record for tuning the corresponding tuning instrument, the recording devices in each row being individual to the station designation in said 20 row.
2. As a new article of manufacture, a chart for tuning radio sets, including a plu-

rality of station designations, and a plurality of recording devices individual to each of said station designations and each 25 of said recording devices corresponding to one of the tuning instruments of the radio set and capable of adjustment to provide a permanent record for tuning the corresponding tuning instrument.

3. As a new article of manufacture, a chart for tuning radio sets, including a base divided into columns and rows, one of said columns containing station designations, and a plurality of recording devices in each column and row, the recording devices in one row being individual to one of said station designations, and the recording devices in each column being individual to one of the tuning instruments of the radio set, said recording devices being capable of adjustment to provide a permanent record for tuning the instruments to which they are individual.

CHARLES F. HANSELMANN.
